IRA O. GRANT, OF CANTON, OHIO, ASSIGNOR OF ONE-HALF TO WILLIAM R. SEESSE,
OF CANTON, OHIO

SPRING SPREADING TOOL

Application filed March 17, 1931. Serial No. 523,267.

My invention relates to tools used in applying or removing automobile springs.

More particularly, my invention relates to a tool for flexing and holding flexed a leaf spring mounted transversely of a vehicle when applying said spring to or removing it from said vehicle.

Various tools or jacks have been devised in the past for accomplishing this purpose, but the great majority of them have embodied a jack which forces one end of the spring outward by applying a pressure between that end of the spring and a shoulder secured to the axle underlying the spring. With this type of tool, the axle may not be removed from the vehicle without removing the spring, and the construction of the standard automobile does not usually permit removal of the spring and axle together.

It has been proposed to provide a tool for spreading such a transverse spring which applies outward pressure between the ends and has no connection with the axle, but difficulty is had with this type of tool in that it tends to twist relative to the spring when outward pressure is applied. This twisting may result in the tool slipping and being thrown out of engagement with the spring with great force due to the tension of the spring. Further difficulty is had in positioning the tool when applying it to the spring.

It is an object of the present invention to provide a simple and inexpensive tool for spreading a leaf spring mounted transversely of a vehicle by exerting outward pressure between the ends thereof, means being provided for preventing twisting of the tool relative to the spring.

A further object is to provide a tool for spreading a transverse spring which tool will, when in operating position, permit removal of the axle of the vehicle and its associated parts.

Another object is to provide means for positioning the tool by engagement with the axle, which means will not interfere with the removal of the axle when the tool is in place.

A still further object is to provide removable means between one end of the tool and

the adjacent end of the spring for preventing creeping of the end of the tool relative to the spring and for preventing locking of the end of the tool.

These and other objects are attained by the improvements comprising the present invention, as will be hereinafter pointed out in detail.

In general terms, the invention includes a bar having one end adapted to engage an end of the spring behind the spring eye, the other end of the bar having a downwardly depending leg adapted to rest upon the axle housing of the vehicle, a bolt threaded through the leg and extending outwardly therefrom, and a detachable substantially semi-cylindrical collar adapted to engirdle the eye adjacent the end of the bolt, the collar being provided with a socket adapted to be disposed above the axis of said eye for receiving the end of the bolt.

A preferred embodiment of the present improvements is illustrated in the accompanying drawing in which

Figure 1 is a fragmentary rear end elevation of an automobile having a leaf spring mounted transversely thereof, showing the tool applied to the spring for installing the same;

Fig. 2 is a similar view showing the tool holding the spring in fully spread position, the axle and associated parts being represented in dot-dash lines to indicate that the same may be removed with the tool in position;

Fig. 3 is a detached perspective view of the tool and the associated spring-eye collar; and

Fig. 4 is a detached perspective view of the collar.

Similar numerals refer to similar parts throughout the several views.

The rear axle housing of an automobile is indicated at 10, having at its central portion the differential housing 11. Rear wheels are journaled on the ends of the axle housing 10 in the usual manner and include spokes 12 and 12' and brake housing members 13 and 13', respectively.

The usual brake mounting members 14 and

14' are secured to the axle housing 10 in a well known manner.

The rear transverse spring is indicated generally at 15, and preferably is secured at its central portion by U bolts 16 to a curved channel member 17, which is in turn secured to the frame 18 of the automobile. The main plate 19 of the spring has its ends curved upon themselves in the usual manner to form the spring eyes 20 and 20'.

10 Ears 21 and 21' are secured to the brake members 14 and 14' respectively. A spring shackle 22 is pivotally connected at one end to the ear 21 and at its other end is adapted to be pivotally connected to the eye 20 of the spring 15. Likewise a spring shackle 22' is pivotally connected at one end to the ear 21' and at its other end is adapted to be pivotally connected to the eye 20' of the spring 15.

20 The improved spreading tool is indicated generally at 23, and includes the bar 24, preferably of rectangular cross section, and having the upwardly angled blade portion 25 at one end for engaging behind one eye of the spring 15, the blade 25 being shown in Figs. 1 and 2 as engaging the main plate 19 of the spring and the eye 20'.

The bar 24 has a downwardly depending leg 26 at its other end adapted to rest upon the axle housing 10 when the tool is in position. The central longitudinal portion of the bar 24 is preferably upwardly curved as at 27 to clear the differential housing 11 at all times.

30 A bolt 28, threaded throughout its length, is preferably screwed through the leg 26 substantially at right angles thereto, and is adapted to be extended and withdrawn relative to said leg by applying a wrench or suitable tool to the head 28a.

40 A substantially semi-cylindric collar 29 is preferably provided for slidably engirdling the eye of the spring, and is shown in Figs. 1 and 2 as applied to the eye 20. A substantially conical socket 30 is provided in the outer surface of the collar 29, and is adapted for receiving the pointed or conical end 28b of the bolt when the same is outwardly extended toward the eye 20 of the spring. The socket 30 is so located that it will be disposed above the axis of the eye 20 when the end of the bolt 28b is inserted therein and pressure is applied by turning the screw bolt 28.

50 Thus, when the bolt is screwed outwardly from the leg 26 to apply outward pressure between the ends of the spring 15, the tool will be wedgably held in position between the eyes of the spring, and the slidable collar 29 will prevent creeping of the bolt and at the same time prevent locking between the end 60 of the bolt and the spring eye 20.

A lock nut 31 is preferably provided upon the bolt 28 for locking the bolt in adjusted position by screwing the nut into abutment with the leg 26.

65 When it is desired to install the spring 15

upon an automobile, the spring is first attached to the frame 18 by means of the U bolts 16, the body of the automobile being suspended by any convenient means such as a chain hoist. The tool 23 with the bolt 28 retracted as shown in Fig. 3, is then positioned with the blade 25 engaging back of one of the eyes as the eye 20', and with the leg 26 resting upon the axle housing 10.

The collar 29 is then positioned around the other eye 20 of the spring and the bolt screwed outwardly until its end 28b enters the socket 30, thus holding the collar in the position shown in Figs. 1 and 2. By further screwing the bolt outwardly the eyes of the spring will be spread apart as shown in Fig. 1, the leg 26 sliding along the axle housing 10 and acting to prevent twisting of the tool relative to the spring.

75 When the spring has been spread sufficiently, the eyes 20 and 20' may be lined up with the free ends of the shackles 22 and 22' respectively, by manipulation of the chain hoist. The shackle bolts may then be inserted and the tool removed.

80 When it is desired to remove the spring from the automobile, the above procedure is reversed.

85 If it should be desired to take out the rear end of the automobile for the purpose of making repairs thereon, that is, to remove the rear wheels, rear axle and housing as a unit, the same may be done by one man with the aid of the improved tool. The spring spreading tool is inserted between the eyes 90 of the spring as shown in Fig. 2, the collar 29 having been first applied, and the shackles 22 and 22' are then disconnected from the eyes 20 and 20' respectively. The bolt 28 may then be screwed inwardly sufficiently to allow the spring eyes to clear the shackles. In this position of the spring and tool the rear end may be easily removed, repaired and replaced.

95 Thus the operations of applying or removing the spring or of removing the rear end of the automobile are facilitated and the expense involved incident to time and labor required is greatly reduced.

100 It will be apparent from the foregoing that the improved spring spreading tool is easily and economically manufactured and is extremely simple in operation. It is to be understood that the various modifications in the present improvements may be made without departing from the scope of the invention as defined in the appended claims.

110 I claim:

1. A spring spreading tool including a bar having one end adapted for engaging behind an eye of a transversely located automobile spring overlying an axle, a downwardly depending leg at the other end of the bar for resting upon the axle to space the bar above the axle, detachable means for slidably en-

girdling the other eye of the spring, and extension means mounted for longitudinal movement on the depending leg and adapted to engage said engirdling means.

- 5 2. A spring spreading tool including a bar having an upwardly angled blade at one end adapted for engaging behind an eye of a transversely located automobile spring overlying an axle, a downwardly depending leg
- 10 at the other end of the bar for resting upon the axle to space the bar above the axle, detachable means for slidably engirdling the other eye of the spring, and a bolt threaded through the leg and adapted to be extended through the eye of the spring outwardly for engagement with said eye engirdling means.
- 15 3. A spring spreading tool including a bar having an upwardly angled blade at one end adapted for engaging behind an eye of a transversely located automobile spring overlying an axle, a downwardly depending leg at the other end of the bar for resting upon the axle to space the bar above the axle, a bolt threaded through the leg and adapted to be extended outwardly therefrom, a lock nut on the bolt adapted to abut said leg, and a detachable collar slidably engirdling the other eye of the spring and provided with a socket normally located above the axis of
- 20 said eye for receiving the outer end of the bolt.
- 25
- 30

In testimony that I claim the above, I have hereunto subscribed my name.

IRA O. GRANT.
